CLAIM

The ornamental design for a cooking basket, as shown and described.

DESCRIPTION

FIG. 1 is an upper perspective view of a cooking basket, showing our new design;

FIG. 2 is a lower perspective view of the embodiment shown in FIG. 1;

FIG. 3 is a front view of the embodiment shown in FIG. 1;

FIG. 4 is a rear view of the embodiment shown in FIG. 1;

FIG. 5 is a side view of the embodiment shown in FIG. 1;

FIG. 6 is another side view of the embodiment shown in FIG. 1;

FIG. 7 is a top view of the embodiment shown in FIG. 1; and,

FIG. 8 is a bottom view of the embodiment shown in FIG. 1.

The broken lines in the figures are for environmental purposes only and form no part of the claimed design.

The dash dot lines represent boundary lines between claimed and unclaimed subject matter.

1 Claim, 6 Drawing Sheets

Related U.S. Application Data

continuation of application No. 29/659,576, filed on Aug. 9, 2018, now Pat. No. Des. 903,413.
